UNITED STATES PATENT OFFICE.

BENJAMIN HOWARD, OF HANWELL, ENGLAND, ASSIGNOR TO THE LONDON GENERAL OMNIBUS COMPANY LIMITED, OF WESTMINSTER, LONDON, ENGLAND.

WHEEL GUARD FOR VEHICLES.

1,412,524.

Specification of Letters Patent. Patented Apr. 11, 1922.

Application filed June 5, 1920. Serial No. 386,729.

(GRANTED UNDER THE PROVISIONS OF THE ACT OF MARCH 3, 1921, 41 STAT. L., 1313.)

To all whom it may concern:

Be it known that I, BENJAMIN HOWARD, a subject of the King of England, residing at Hanwell, Middlesex, England, have invented certain new and useful Improvements in Wheel Guards for Vehicles, (for which on May 12, 1914, I filed application No. 11,741 for British patent,) of which the following is a specification.

10 This invention relates to wheel-guards for vehicles its object being to provide an improved construction of such device, which shall be simple and efficient. A common fault with devices of this kind, such as have 15 hitherto been proposed, has been the tendency to pin an obstacle of small height, such for example as an arm or hand to the ground thus involving a person in injury to a limb even though the body of the person be protected.

It has many times been proposed to provide a buffer-rail in front of the wheels of a vehicle such rail being supported by mechanism so that when the forward part 25 of the rail or some member operatively connected therewith is struck, the rail drops on to the road or low enough to prevent any object from passing beneath it. Further, it has been proposed to provide such buffer- 30 rails with an inflatable tube at the front to constitute a cushion-device.

It will be appreciated that where a device has to be dropped by the impact of, say, a person knocked down by the vehicle, a limb 35 or some part of the body of such person is likely to be pinned beneath the wheel-guard, in which case the wheel-guard may do considerable damage itself by riding up over the limb and even over the body of the person 40 and it may thus be rendered practically inoperative.

Fixed buffer-rails have been proposed with or without pneumatic or other cushioning devices, but it is not practicable to have 45 these fixed so low as to prevent the hand or a limb of a person knocked down, from getting beneath them, with the result that considerable damage may be done to the limb, and moreover, the limb thus being pinned 50 down, the body of the person may be swung round against the vehicle.

The object of the present invention is to

provide an impact-device, hereinafter referred to as a cushion, in front of the wheels, which does not depend upon any drop action, is high enough from the road to clear the same, but low enough and so constructed that when it strikes an object it will yieldingly close up the space between it and the road.

According to this invention the wheel-guard comprises a fixed support whereon is mounted an impact-cushion of flexible and resilient material (for example a fabric built up of alternate layers of rubber and canvas) having its lower face towards and near the road and being connected to the support fore and aft (for example by upwardly-directed continuations of the same material) and so constructed that it is readily deformable downwardly along a line at right angles to the direction of travel by impact against the front of the cushion, the proportions of the deformable parts of the cushion being such relatively to the distance 75 of the under-face of the same from the road that when the impact against the front of the cushion takes place, the said face is driven downwards in the form of a flexible fold or tongue whose lower edge approximately makes contact with the road for the purpose above described.

Preferably the impact-device is in the form of a loop or tube which is downwardly and forwardly directed from its support, the 85 under-side of such tube constituting the aforesaid downwardly deformable face, the cross-sectional diameter of the loop or tube and the stoutness of the material composing the same, being such as to operate in the 90 manner previously described.

Where a tube is employed, a backing-plate may be provided on the support which extends from a point about half-way up the tube, whose throughway lies horizontally at 95 right-angles to the direction of travel of the vehicle, to a point near the top of the tube. A rigid backing is thus provided for the rearward and upper portion of the tube which the better ensures the desired action 100 of the tube.

A number of short sections of tube may be used placed end-to-end, and, if desired, spaced apart across the front of the vehicle

or any part where it is desired to apply the invention.

Means may be provided for adjusting the height of the impact-device from the road.

Conveniently the under-face of the impact-device may be formed of, or provided with, india-rubber or other friction-producing material, so that upon contact with an obstacle of too small a height to strike the impact-face of the device properly, such as the hand of a person, the friction with the obstacle will carry the latter along over the roadway free from serious injury.

In the accompanying drawings:—

Figure 1 is a front elevation of a life-guard device constructed according to one method of carrying out this invention;

Figure 2 is a plan of the same;

Figure 3 is a detail section on line 3—3 of Figure 2;

Figure 4 is a detail showing the attachment of the wheel guards to the frame;

Figure 5 shows a plan of a modification of the construction of a portion shown in Figures 1 and 2;

Figures 6 and 7 are elevation and plan respectively of a modification showing an application of this invention to a rear wheel; and

Figure 8 is a side view of a device constructed according to the present invention as applied for use between the front and rear wheels of a vehicle.

The same reference characters indicate the same parts in all the figures.

A wheel-guard is provided for each front wheel and turns with it in its turning movements. This wheel-guard comprises a G-shaped supporting bracket A having an external stiffening rib A¹, which is mounted to turn upon the pivot-pin A² about which the front wheel turns. The bracket is so shaped as to engage this pin at both its upper and lower ends and so works firmly and easily

thereon. To the rib A¹ of the bracket A is bolted a wood and steel framework or shield A³ which extends forwardly from the bracket inside the wheel and outwardly in front of the wheel. The lower edge A⁴ of the shield A³ is arranged close to the ground, and carries an impact-receiving cushion as herein-after described. In order that the two shields A³ may turn about the pivots A² in unison with the steering movements of the

wheels, the brackets A have rearward extensions A⁵ which carry studs A⁶ engaged by lugs A⁷ on the steering mechanism of the front wheels. This steering mechanism is of the usual kind and comprises two levers C and C¹ each secured to the axle of one of the front wheels and connected together by a cross-bar C². The lugs A⁷ are mounted on the levers C and C¹ and are nearer the centre of the vehicle than the studs A⁶, so that they

can act upon the studs A⁶ and extensions A⁵

to push them outwardly from the centre. Such an action of course moves the shields A³ and attached parts of the wheel-guard inwardly. The extensions A⁵ are drawn together and held against the lugs A⁷ by the spring A⁸ connected to each of them by rods A⁹. As previously stated, the shields A³ are bent outwardly at their forward ends in front of the front wheels, and it will be readily understood that if one of these shields should strike any obstacle, such as a curb-stone, the spring A⁸ permits it to yield inwardly, turning about the pivot A² independently of the wheel, but normally the lugs A⁷ on the steering mechanism cause the shields to turn in unison with the steering movements of the wheels.

The shields A³ are carried downwards close to the ground and rearwardly between the wheels. Along the lower edges A⁴ of the shields there are secured stout impact-receiving cushions B formed of sections of rubber and canvas hose. As shown in Figure 3, the cushion is secured to the shield between a backing-plate B¹ and a clamping-plate B². A backing-plate B³ formed by an extension of the plate B¹ extends over the upper rear portion of the cushion. It will be seen that the backing-plate B³ together with the shields A³ constitutes a rigid support for the cushions or impact-devices B.

The under-face B⁴, Figure 3, of the cushion curves downwardly towards the road so that it has a bias in that direction when the face B⁴ strikes an obstacle, and the fact that the parts B⁴, B⁵ may be viewed as a loop or tube which projects forwardly and downwardly from the plate B³, tends to increase the downward movement of the part B⁵ when the part B⁴ is struck.

It will be seen that the throughway of the forward end of the tube B is horizontal and at right-angles to the direction of travel. The tube is extended down the side faces of the edges A⁴ of the shields A³ where its throughway is not at right-angles to the direction of travel, but it is not so effective when thus placed obliquely to the direction of travel. A suitable construction of the cushion has been found to be a hose about 7 inches in external diameter formed of about 7-ply canvas and rubber alternately with a total thickness of wall of about three-quarters of an inch. The lower edge of the cushion may be about three-quarters of an inch from the ground level, but this distance may be slightly increased or diminished as desired.

In order to protect the cushion from wear by accidental contact with a road surface or objects thereon, it may be provided with a single row of steel studs, but care must be taken to place these so that they do not interfere with the frictional action between the cushion and an obstacle of small height.

In order to provide for the vertical adjustment of the cushion, the shield A³ is connected to the bracket A by bolts A¹¹ and a series of bolt-holes A¹² is provided in the 5 web of the bracket so that the shield may be secured thereto in a number of positions corresponding to the various holes.

Between the wheels, another guard is provided secured to the cross-member D of the 10 chassis of the vehicle. This consists of several short sections E of rubber and canvas hose, each mounted on a vertical supporting member E¹ bolted to the cross-member D of the frame. The vertical supports 15 E¹ are further connected together by a horizontal bar E². In order to provide for the vertical adjustment of this life guard, a series of bolt-holes E³, E⁴ is provided in each of the supports E¹ so that it may be 20 bolted to the cross-member D in a number of different positions nearer to or further from the ground level. Each of the cushions E is provided with a constraining-plate E⁵.

25 In the modification shown in Figure 5, the inclined portion extending from a position just in advance of the wheel to a position beneath the front axle is replaced by a series of short cushions B⁶ arranged step- 30 wise.

The construction shown in Figures 6 and 7, having a cushion F, is very similar to that hereinbefore described with reference to Figures 1 and 2 except that as applied to 35 a rear wheel provision does not have to be made for any pivotal movement of the wheel.

Short cushions may also be employed, one at each end of a guard H as seen at G³ in 40 Figure 8, placed between the front and rear wheels of a vehicle.

It will be appreciated that each cushion or tube, B, F or G³, provides an under part of flexible and resilient material with its 45 face near the road, which under part is connected fore and aft by the continuation of the material upwardly to the support or backing-plate B³. The tube thus constitutes a loop of material whose under-side has a 50 bias downwards so that it is readily deformable downwardly along a line at right-angles to the direction of travel when impact takes place against the front of the cushion and the said under part is placed near enough to 55 the road and is sufficiently deformable, so that when the tube is struck at the front, the under-face is forced down approximately into contact with the road. The part thus forced down is in the form of a 60 flexible fold or tongue which obviates or reduces the risk of a portion of the obstacle, for example the hand or part of a person's clothing, from passing beneath the cushion. In the case, however, in which what is first 65 encountered is of small height, such for ex-

ample as the hand of a person, the friction between the rubber surface of the cushion and the hand will serve to brush or sweep the hand along over the ground until fuller impact occurs with the person, which full 70 impact is taken by the body of the cushion and results in the person being carried bodily along free from serious injury.

It has been proposed to use a solid rubber or pneumatic buffer on a spring-carried 75 frame in front of a vehicle wheel, which buffer projected forwardly and was sufficiently resilient to enable it to be forced down by the impact of any object upon the upper side of it.

It has also been proposed to support a pneumatic tube on a buffer-rod by a backing-plate extending approximately from the top of the tube down to a point near the bottom of the same, but this buffer-rod was 80 arranged to drop when struck by an obstacle. When the buffer-rod was in the dropped position the tube formed a downwardly and forwardly projecting loop on the rod, but being carried on a movable 85 frame and being inflated, its action would not be the same as the impact-device according to the present invention.

No claim is made for either of these two 90 last-described arrangements.

What I claim as my invention and desire to secure by Letters Patent is:—

1. A wheel-guard for a vehicle comprising a support, an impact-cushion of flexible and resilient material having its lower face towards and near the road, and means for mounting said impact-cushion on the support in such a manner that it is connected thereto fore and aft, said impact-cushion being so constructed that it is readily deformable downwardly along a line at right-angles to the direction of travel by impact against the front of the cushion, and the proportions of the deformable parts of the cushion being such relatively to the distance of the under face of the same from the road that when the impact against the front of the cushion takes place, the said face is driven downwards in the form of a flexible fold or tongue whose lower edge approximately makes contact with the road for the purpose described.

2. A wheel-guard for a vehicle comprising a support, an impact-cushion of flexible and resilient material having its lower face towards and near the road, and means for mounting said impact-cushion on the support in such a manner that it is connected thereto fore and aft by upwardly-directed continuations of the support, said impact-cushion being so constructed that it is readily deformable downwardly along a line at right-angles to the direction of travel by impact against the front of the cushion, and the proportions of the deformable parts 120 125 130

of the cushion being such relatively to the distance of the under face of the same from the road that when the impact against the front of the cushion takes place, the said 5 face is driven downwards in the form of a flexible fold or tongue whose lower edge approximately makes contact with the road for the purpose described.

3. A wheel-guard for a vehicle comprising 10 a support, an impact-cushion of flexible and resilient material built up of alternate layers of rubber and canvas and having its lower face towards and near the road, and means for mounting said impact-cushion on the 15 support in such a manner that it is connected thereto fore and aft, said impact-cushion being so constructed that it is readily deformable downwardly along a line at right-angles to the direction of travel 20 by impact against the front of the cushion, and the proportions of the deformable parts of the cushion being such relatively to the distance of the under face of the same from the road that when the impact against the 25 front of the cushion takes place, the said face is driven downwards in the form of a flexible fold or tongue whose lower edge approximately makes contact with the road, for the purpose described.

30 4. A wheel-guard for a vehicle comprising a support, an impact-cushion having its lower face towards and near the road, and means for mounting said impact-cushion on the support in such a manner that it is connected 35 thereto fore and aft, said impact-cushion being in the form of a loop which is downwardly and forwardly directed from the support, is of flexible and resilient material whose underside constitutes a face that 40 is readily deformable downwardly along a line at right-angles to the direction of travel by impact against the front of the cushion and the cross-sectional diameter of the loop and the stoutness of the material composing 45 the same being such that when the impact against the front of the cushion takes place, the said face is driven downwards in the form of a flexible fold or tongue whose lower edge approximately makes contact with the 50 road, for the purpose described.

5. A wheel-guard for a vehicle comprising a support, an impact-cushion having its lower face towards and near the road, and means for mounting said impact-cushion on the 55 support in such a manner that it is connected thereto fore and aft, said impact-cushion being in the form of a tube which is downwardly and forwardly directed from the support, is of flexible and resilient material whose underside constitutes a face that is 60 readily deformable downwardly along a line at right-angles to the direction of travel by impact against the front of the cushion and the cross-sectional diameter of the tube and the stoutness of the material 65

composing the same being such that when the impact against the front of the cushion takes place, the said face is driven downwards in the form of a flexible fold or tongue whose lower edge approximately 70 makes contact with the road, for the purpose described.

6. A wheel-guard for a vehicle, comprising an impact cushion in the form of a tube, a support having a concave wall constituting a backing for the tube, and means attaching one side of said tube to the support in such a manner that the tube is directed downwardly and forwardly from the support so as to have its lower face 80 situated substantially nearer the road than is the bottom of the support, said backing extending from a point approximately half-way up and behind the tube towards the top of the same. 85

7. A wheel-guard for a vehicle, comprising an impact cushion in the form of a tube, a support having a curved wall constituting a backing for the tube, and means attaching one side of said tube to the support in such a manner that the tube is directed downwardly and forwardly from the support so as to have its lower face situated substantially nearer to the road than is the bottom of the support, said 90 backing extending upwards from a point approximately half-way up and behind the tube, and downwards from a point below the top of the tube. 95

8. A wheel-guard for a vehicle, comprising an impact-device in the form of a plurality of short sections of open-ended loops, concave supports for said sections, and means for mounting said sections against the concave walls of the supports with their through-way axes at right-angles to the direction of travel of the vehicle, the concave walls of the supports providing each a backing for a section which extends from a point approximately half-way up and behind the section towards the top of the same, for the purpose described. 100

9. A wheel-guard for a vehicle comprising a support, an impact-cushion of flexible and resilient material having its lower face 115 towards and near the road and formed of friction-producing material, and means for mounting said impact-cushion on the support in such a manner that it is connected thereto fore and aft, said impact-cushion being so constructed that it is readily deformable downwardly along a line at right-angles to the direction of travel by impact against the front of the cushion, and the proportions of the deformable parts of the cushion being such relatively to the distance of the underface of the same from the road that when the impact against the front of the cushion takes place, the said face is 120 driven downwards in the form of a flexible 125 tongue whose lower edge approximately makes contact with the road, for the purpose described. 130

fold or tongue whose lower edge approximately makes contact with the road, for the purpose described.

10. A well-guard for a vehicle comprising a support, an impact-cushion of flexible and resilient material having its lower face towards and near the road and there provided with a rubber friction surface, and means for mounting said impact-cushion 10 on the support in such a manner that it is connected thereto fore and aft, said impact-cushion being so constructed that it is readily deformable downwardly along a line at right-angles to the direction of travel by impact against the front of the cushion, and the proportions of the deformable parts of the cushion being such relatively to the distance of the underface of the same from the road that when the impact against the 15 front of the cushion takes place, the said face is driven downwards in the form of a flexible fold or tongue whose lower edge approximately makes contact with the road, for the purpose described.

25. 11. A wheel-guard for a vehicle comprising a support, an impact-cushion in the form of a tube having its lower face towards and near the road and there provided with a rubber friction surface, and means for 30 mounting said impact-cushion on the support in such a manner that the support provides a backing for it which extends from a point approximately half way up and behind the tube towards the top of the 35 same, for the purpose described.

12. A wheel-guard for a vehicle comprising an impact-cushion of flexible and resilient material having its lower face towards and near the road, supports for said 40 cushion to which it is connected fore and aft and whereby it is carried in front of a steering wheel of the vehicle, said cushion being so constructed that it is readily deformable downwardly along a line at right-angles to the direction of travel by impact 45 against the front of the cushion, and the proportions of the deformable parts of the cushion being such relatively to the distance of the underface of the same from the road that when the impact against the 50 front of the cushion takes place, the said face is driven downwards in the form of a flexible fold or tongue whose lower edge approximately makes contact with the road, 55 and means for turning said support in unison with the supports of the wheel.

13. A wheel-guard for a vehicle comprising an impact cushion having its lower face towards and near the road, a support for 60 said cushion, means for mounting said cushion on the support in such a manner that it is connected thereto fore and aft and is carried in front of a steering wheel of said vehicle, said cushion being in the form of a 65 tube which is downwardly and forwardly

directed from the support, is of flexible and resilient material whose underside constitutes a face which is readily deformable downwardly along a line at right-angles to the direction of travel by impact against the 70 front of the cushion, and the cross-sectional diameter of the tube and the stoutness of the material composing the same being such that when the impact against the front of the cushion takes place, the said face is 75 driven downwards in the form of a flexible fold or tongue whose lower edge approximately makes contact with the road, and means for turning said support in unison with the steering movements of the wheel. 80

14. A wheel-guard for two steering wheels of a vehicle comprising for each wheel an impact-cushion in the form of a tube having its lower face towards and near the road, a support for each cushion, means 85 for mounting said cushion on the support in such a manner that the support provides a backing for it which extends from a point at approximately half way up and behind the tube towards the top of the same, and 90 means for turning said supports in unison with the steering movements of the wheels, said cushions being adapted to move yieldingly and independently of the wheels toward the centre of the vehicle, for the purpose described.

15. A wheel-guard for the steering wheel of a vehicle comprising an impact-cushion in the form of a tube having its lower face towards and near the road, a support for 100 said cushion, means for mounting said cushion on the support in such a manner that the support provides a backing for it which extends from a point approximately half way up and behind the tube towards the top 105 of the same, means, including a lug, for steering the vehicle wheel and resilient means for holding the cushion against said lug, which latter is adapted to move the cushion inwardly towards the centre of the 110 vehicle.

16. A wheel-guard for two steering wheels of a vehicle comprising for each wheel an impact-cushion in the form of a tube having its lower face towards and near the 115 road, a support for each cushion, means for mounting said cushion on the support in such a manner that the support provides a backing for it which extends from a point approximately half way up and behind the 120 tube towards the top of the same, means including a lug at each side of the vehicle, for steering the vehicle wheel and resilient means connecting the cushions together and holding them against said lugs, which latter are adapted to move the cushions inwardly towards the centre of the vehicle.

17. A wheel-guard for two steering wheels of a vehicle comprising for each wheel an impact-cushion of flexible and resilient ma- 130

terial having its lower face towards and near the road, a support for each cushion, means for mounting each impact-cushion on a support in such a manner that it is connected thereto fore and aft, said impact-cushions being so constructed that they are readily deformable downwardly along a line at right-angles to the direction of travel by impact against the front of the cushions, and the proportions of the deformable parts of the cushions being such relatively to the distance from the underfaces of the same from the road that when the impact against the front of the cushions takes place, the said faces are driven downwards in the form of flexible folds or tongues whose lower edges approximately make contact with the road, means including a lug at each side of the vehicle, for steering the vehicle wheel and resilient means connecting the cushions together and holding them against said lugs, which latter are adapted

to move the cushions inwardly towards the centre of the vehicle.

18. A wheel-guard for a vehicle, comprising an impact cushion in the form of an open-ended transverse flexible tube which is stiff enough to maintain its shape when not in collision with an obstacle, a supporting backing plate for the tube, means attaching one side of the tube to the plate in such a manner that the tube is directed downwardly and forwardly from the plate with its through-way axis approximately horizontal and at right angles to the direction of travel of the vehicle, said plate extending from a point approximately half way up and behind the tube towards the top of the same, and means adjustable in height from the ground for mounting said support on a vehicle.

In testimony whereof I affix my signature.

BENJAMIN HOWARD.
